WALL AND CEILING COVERING.

No.19,616.

Patented Jan. 28, 189

UNITED STATES PATENT OFFICE.

PAUL GROEBER, OF RUTHERFORD PARK, NEW JERSEY, ASSIGNOR TO
FREDERICK BECK, OF NEW YORK, N. Y.

DESIGN FOR A WALL AND CEILING COVERING.

SPECIFICATION forming part of Design No. 19,616, dated January 28, 1890.

Application filed December 26, 1889. Serial No. 335,047. Term of patent 3½ years.

To all whom it may concern:

Be it known that I, PAUL GROEBER, a citizen of the United States, residing at Rutherford Park, in the county of Bergen and State of

5 New Jersey, have invented and produced a new and original Design for a Wall and Ceiling Covering, of which the following is a specification, reference being had to the accompanying drawing, forming part thereof.

10 The leading feature of my design consists of a series of scrolls 1, having offshoots of leaves and terminating with an entwining ribbon ornament of four different patterns

2, 3, 4, and 5. These ribbon ornaments are enriched in all cases with small rosettes 6. 15

The groundwork of the general design is granulated.

What I claim is—

The design for a wall and ceiling covering herein shown and described, consisting of 20 scrolls, ribbon-shaped ornaments, and rosettes.

PAUL GROEBER.
